UNITED STATES PATENT OFFICE.

HENRY A. HAMILTON, OF EMLENTON, PENNSYLVANIA.

DESIGN FOR A BRUSH.

SPECIFICATION forming part of Design No. 33,070, dated August 14, 1900.

Application filed April 7, 1900. Serial No. 12,022. Term of patent 7 years.

To all whom it may concern:

Be it known that I, HENRY A. HAMILTON, a citizen of the United States, residing at Emlenton, in the county of Venango and State of Pennsylvania, have invented and produced a new and original Design for a Brush; and I do hereby declare the following to be a full, clear, and exact description of the same, reference being had to the accompanying drawing, forming a part thereof.

This invention relates to a new and original design for a brush; and it consists in the shape and configuration of the brush hereinafter described and as shown in the drawing.

15 In the drawing the design is shown in perspective.

The brush is provided with an open marginal frame A, generally oblong and rounded at the corners and having extending longitudinally from one end thereof a handle B. The open frame A is formed of a rod or strip rounded in cross-section. Extending from one side to the other of the frame A are a se-

ries of parallel bars which are smaller in cross-section than the frame bar or strip and which, 25 it will be seen, extend transversely of the frame or crosswise of the longitudinal handle B. Bristles project from the parallel transverse frame-bars.

The essential features of the design reside 30 in the brush-head frame of generally oblong shape and having a longitudinally-extending handle and transversely-arranged bars connecting the side bars of the frame, substantially as shown.

Having thus described the invention, what is claimed as new, and desired to be secured by Letters Patent, is—

The design for a brush substantially as herein described and shown.

40 In testimony whereof I affix my signature in presence of two witnesses.

HENRY A. HAMILTON.

Witnesses:

II. R. GILMORE,
C. H. PERRINE.
